United States Patent Office

Des. 226,278
Patented Feb. 6, 1973

226,278

GOLF CLUB

Samuel Lombardo, 3419 Corinna Drive,
Palos Verdes Peninsula, Calif. 90274

Filed July 23, 1971, Ser. No. 165,874

Term of patent 14 years

Int. Cl. D21—02

U.S. Cl. D34—5

FIG. 1 is a left side view of a golf club showing my new design;

FIG. 2 is a right side view of the golf club shown in FIG. 1;

FIG. 3 is a rear view of the golf club shown in FIG. 1;

FIG. 4 is a front view of the golf club shown in FIG. 1;

FIG. 5 is a top view of the golf club shown in FIG. 1; and

FIG. 6 is a bottom view of the golf club shown in FIG. 1.

I claim:

The ornamental design for a golf club, substantially as shown.
